UNITED STATES PATENT OFFICE.

DAVYDD C. HUGHES, OF CHICAGO, ILLINOIS, ASSIGNOR TO D. C. HUGHES & COMPANY,
OF CHICAGO, ILLINOIS, A CORPORATION OF ILLINOIS.

ELECTRIC SAD-IRON.

1,243,412.

Specification of Letters Patent. Patented Oct. 16, 1917.

Application filed January 15, 1917. Serial No. 142,440.

To all whom it may concern:

Be it known that I, DAVYDD C. HUGHES, a citizen of the United States, and resident of Chicago, county of Cook, and State of Illinois, have invented certain new and useful Improvements in Electric Sad-Irons, of which the following is a specification, and which are illustrated in the accompanying drawings, forming a part thereof.

10 The invention relates to sad irons provided with electric heating elements, its objects being to generally improve the iron and the electric elements thereof.

The invention consists in the arrangement 15 of the heating elements along the side walls of the base; to means for clamping the elements against these walls; to the structural formation of the heating elements, and to improved means for electrically connecting 20 these elements together and to the terminals of the iron; and to the mounting of the terminals upon the base of the iron.

The invention is illustrated in the accompanying drawings, in which—

25 Figure 1 is a plan view of the iron with its cover plate and handle removed;

Fig. 2 is a sectional view on the line 2—2 of Fig. 1;

30 Fig. 3 is a detail section on the line 3—3 of Fig. 1, shown in perspective;

Fig. 4 is a detail section on the line 4—4 of Fig. 1;

Fig. 5 is a vertical longitudinal central section of the iron, partly in elevation;

35 Fig. 6 is a detail section on the line 6—6 of Fig. 5; and

Fig. 7 is a view in perspective of the wedge-block for forcing the elements against the walls of the iron.

40 The iron comprises a chambered base 10 and a cap or cover plate 11, adapted to fit upon the base and to be secured thereto by any suitable means, such as the screws 12. The handle 13 is of ordinary construction, 45 and may be secured to the cap 11 by means of the screws 12, as shown.

The iron is of the usual pointed form. Its side walls 14 are thin and their inner surfaces substantially vertical. A lining 15, 50 of insulating material, is applied to these surfaces, and the heating elements, generally designated by the numerals 16, 17, rest and are compressed against this lining.

55 A pair of clamping blocks 18, 19, are applied to the inner faces of the heating ele-

ments, the outer faces of such blocks conforming to the inner surfaces of the side walls 14 of the base, their inner faces preferably being straight and there being upon such face of each a vertical rib 20, 21, inclined inwardly from top to bottom. A wedge-block 22, channeled, as shown at 23, 24, to receive the ribs 20, 21, forces the clamping blocks outwardly as it is drawn down, by means of a screw-bolt 25 threaded 60 into a socket in a boss 26 formed on the bottom of the base 10. By reason of the curved form of the side walls of the base and of the outer faces of the clamping blocks, the clamping pressure is applied to 70 the heating elements uniformly from end to end.

Each of the elements 16, 17, comprises a core 27 of insulating material, such as mica, and a sheet 28 of soft material, such as 75 asbestos, of slightly greater width than the core and overlapping each of its edges, and a coil 29 of resistance wire helically wound about the core and the asbestos sheet, its several turns being spaced apart. In applying the wire it is drawn as tightly as the fragile character of the coil will permit, and embeds itself in the asbestos, bending the margins thereof over the edges of the core, as shown in Fig. 3, thereby protecting the 85 core from injury during the operation of manufacture and also anchoring the several turns of the wire and insuring their permanent spacing. After the parts have been thus assembled the entire element is placed 90 in a press to flatten down the wire intermediate of the edges of the core, this operation tending to embed the wire in the asbestos matrix throughout its entire width. The overlapping margins of the matrix prevent the wire from taking the form of abrupt angles at the edges of the element, thereby removing the danger of arcing and the consequent burning out of the wire at 95 this point.

100 The coils of the two heating elements are electrically connected at the tip of the iron by means of a metallic plate 30 overlapping the two elements and being applied to either their outer or inner faces, the wedging pressure upon the elements insuring a perfect connection. A lining 31 of insulating material, such as asbestos, is interposed, between the two heating elements and the clamping blocks 18, 19.

110

The coils of the heating elements are connected at their rearward ends with a pair of binding posts 32, 33, by means of a strip of fusible material 34, 35, which will be 5 melted by an abnormally heavy current and thus protect the heating elements from injury.

The binding posts 32, 33, are fixed to the base, preferably through the medium of a 10 bracket 36 mounted thereon and projecting upwardly through an aperture 37 in the cap 11. A plug socket 38 incloses these posts, being attached to the cover 11 as shown at 39, a foot-piece 40 projecting backwardly 15 from the lower end of this socket member to form a rest for the iron when tilted up and out of use. A suitable plug 41, to which the leading in wires 42 are attached, enters the socket 38.

20 For the purpose of insulating the fusible connections 34, 35, from the elements 18, 19, a plate of mica or similar material, as shown at 43, 44, is used and may be secured in place by being folded down between the clamping 25 block of the heating elements.

As thus constructed the iron and its various parts are simple of manufacture and easy of assembling, and the various parts are conveniently removed for purposes of 30 repair. The heating elements are firmly clamped against the side walls of the base and uniformly throughout their entire area, thereby insuring the heating of the metal. The disposition of the heating elements 35 along the side walls of the base and extending to its apex results in the application of the heat to the margins of the iron and its tip, where it is most needed, the central portion of the bottom of the iron being sufficiently hot by conduction. The asbestos 40 lining between the heating elements and the clamping blocks may be of sufficient thickness to prevent excessive heating of these blocks and thus conserve the heat for use 45 in the portions of the iron where it is most required. The open space between the clamping blocks also tends to keep the cap and handle cool.

The outer surface of the cap 11 may be 50 given any desired finish. Preferably this surface is enameled, as indicated at 45, thereby not only giving it a handsome finish but preventing its corrosion.

While I have shown a preferred embodiment 55 of the invention, various changes in detail of construction may be made without departing from its scope.

While the heating element herein shown and described is primarily intended for use 60 in connection with sad irons, it may obviously be employed in connection with other

devices, such as percolators, toasters, etc., and still embody the features of the invention.

I claim as my invention—

1. In an electric sad iron, in combination, a chambered base having side walls, heating elements bearing against the side walls, clamping blocks for holding the heating elements against such walls, and wedge means 70 for advancing the blocks.

2. In an electric sad iron, in combination, a chambered base having side walls, heating elements bearing against the side walls, clamping blocks for holding the heating 75 elements against such walls, and spreading means reacting between the blocks for advancing them.

3. In an electric sad iron, in combination, a chambered base having curved side walls, 80 heating elements bearing against such walls, a pair of clamping blocks having faces conforming to the curvature of the side walls for forcing the elements thereagainst, and spreading means reacting between the 85 blocks.

4. In an electric sad iron, in combination, a chambered base having curved side walls, heating elements bearing against such walls, a pair of clamping blocks having faces 90 conforming to the curvature of the side walls for forcing the elements thereagainst, and a wedge entering between the blocks.

5. In an electric sad iron, in combination, a chambered base having curved side walls, 95 heating elements bearing against such walls, a pair of clamping blocks having faces conforming to the curvature of the side walls for forcing the elements thereagainst, a wedge entering between the blocks, and a 100 screw engaging the base for advancing the wedge.

6. In an electric sad iron, in combination, a chambered base having side walls, heating elements bearing against the side walls, and 105 a connector overlapping the ends of the heating elements.

7. In an electric sad iron, in combination, a chambered body having side walls, heating elements bearing against such walls, a 110 connector overlapping adjacent ends of the elements, and means for binding the connector to the elements and the elements against the walls of the base.

8. In an electric sad iron, in combination, 115 a chambered base, a heating element within the base, binding posts mounted on the base and connected with the heating element, a handle carrying cap covering the base, and a plug socket carried by the cap.
